UNITED STATES PATENT OFFICE

2,442,825

EAR MUFF ARRANGEMENT

Hyman M. Rabushka, Clayton, Mo., assignor to
Premium Cap Company, St. Louis, Mo., a firm

Application May 31, 1946, Serial No. 673,468

3 Claims. (Cl. 2—199)

1

The present invention relates to an ear muff arrangement. More particularly, it relates to an ear muff arrangement for use upon a cap.

It is an object of the invention to provide an ear muff construction for use on caps, which will be inexpensive and yet strong and durable in use. A particular object is to provide a construction that will simplify manufacturing operations.

It is a particular object of the invention to provide a reinforcing clip combination for securing an ear muff device to a cap, which will hold the parts together, permit pivoting of the ear muff to inoperative position, and prevent the ear muff from pulling off the cap.

In the drawing:

Fig. 1 is a perspective view of a cap with the ear muff thereon;

Fig. 2 is a section on the line 2—2 of Fig. 1, the same being a vertical section through the attachment means and the associated parts;

Fig. 3 is a side elevation of the ear muff device with the covering removed from the ear muff frame;

Fig. 4 is a view similar to Fig. 3, but with the ear muff frame turned upward to its retracted position;

Fig. 5 is an enlarged section of the line 5—5 of Fig. 3; and

Fig. 6 is a view of the clip used in this construction.

A cap is shown generally at 10. This may be any style of cap. It includes an outer piece of material 11 turned under and there united by stitching 12 with a lining 13 similarly turned under. The foregoing represents familiar parts of a cap that is lined, although it will appear, from the description to follow, that the lining is not an essential part of the invention.

A stiffening strip 15 is employed in the cap, and it conventionally extends around at least the back part of the lower edge of the cap and is secured in the turned under part of the outer material 11 of the cap. The particular way of securing the stiffening strip is not necessarily a part of this invention.

Ear muffs have heretofore been secured by rivets or similar means to certain ones or all of the foregoing cap elements. It is particularly desirable to secure the ear muff to the stiffening strip. However, owing to the fact that such strip is usually of fibrous or fabric material, the conventional attaching means are apt either to pull out or to deform the stiffening strip. This difficulty has been overcome in the present in-

vention by the use of bent metal clip-like members 16 that preferably have depressed or indented portions 17 therein, as shown more particularly in Fig. 6. The overlapping portions of the clip members are provided with aligned openings 18 and 19.

The clips are slipped over the edge of the stiffening strip 15 at the proper locations for the ear muffs. This may be done after the stiffening strip is sewed into place, if desired. The ear muff has an attaching element 21 to which the ear muff frame 22 is pivotally attached. This element 21 is desirably of metal, or the like. It has a hole to receive a rivet 23 that passes through the cap portion 11, through the hole 18 of the clip 16, through the stiffening strip 15, and then through the other hole 19 of the clip. The rivet has heads outside the element 21 and the inner end of the clip 16 to hold the parts together. The rivet 23 forms a pivot so that the entire ear muff may be pivoted from its full line position of Fig. 1 to the dotted line position. In this operation, the heads of the rivet 23 bear against the metal supporting member 21 and the inner leg of the bracket 16. The bracket is of such size as to distribute any forces applied to the ear muffs and to prevent such forces from pulling the ear muffs out of the cap or out of the stiffening strip.

In the fabrication of caps, the clips 16 may be disposed over the stiffening strip at proper points at any time during the fabrication of the cap. The detents 17 hold them in position until they are secured finally by the rivets 23. Thus, the assembly of the ear muffs onto the cap is a very simple operation.

What is claimed is:

1. An ear muff arrangement for a cap, or the like, which cap includes an outer covering portion of fabric, or the like, and an inner strip, a reinforcing clip having connected legs formed so that the clip may be fitted over the edge of the strip with the legs projecting on opposite faces of the strip and in contact with said faces, the legs of the clip having aligned openings therethrough, an ear muff support, and attachment means rotatably attaching the support onto the cap, the attachment means comprising a rivet-like element extending from the ear muff support through the fabric of the cap, the openings of the clip and the strip, and having an extending end portion on its inner end engaged with the inner leg of the clip.
2. An ear muff arrangement for a cap, or the like, which cap includes an outer covering por-

tion of fabric, or the like, and an inner strip, a reenforcing clip having connected legs formed so that the clip may be fitted over the edge of the strip with the legs projecting on opposite faces of the strip, the legs of the clip having aligned openings therethrough, an ear muff support, and attachment means extending from the ear muff support through the cloth of the cap, the openings of the clip and the strip, and engaged with the inner leg of the clip, said clip having retaining means for engagement with the strip when it is disposed thereover.

3. An ear muff arrangement for a cap, or the like, which cap includes an outer covering portion of fabric, or the like, and an inner strip, a reenforcing clip having connected legs formed so that the clip may be fitted over the edge of the strip with the legs projecting on opposite faces of the strip, the legs of the clip having aligned

openings therethrough, an ear muff support, and attachment means extending from the ear muff support through the cloth of the cap, the openings of the clip and the strip, and engaged with the inner leg of the clip, said clip having retaining means for engagement with the strip when it is disposed thereover, said retaining means comprising a detent portion formed by a depression in at least one of said legs of said clip.
